Primary Examiner — John A Voytek(74) Attorney, Agent, or Firm — Leveque IP Law, P.C.(57) CLAIM

The ornamental design for an emblem with legacy number, as shown and described.

DESCRIPTION

FIG. 1 is a front perspective view of a design for an emblem with legacy number;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof; and,

FIG. 8 is a front perspective view of a design for an emblem with legacy number shown with an unclaimed design disposed around the emblem.

The broken lines depict portions of the emblem with legacy number that form no part of the claimed design.
